UNITED STATES PATENT OFFICE

171,754

HAT OR THE LIKE

Jack Endelson, New York, N. Y.

Application August 6, 1952, Serial No. 20,925

Term of patent 3½ years

(Cl. D3—13)

To all whom it may concern:

Be it known that I, Jack Endelson, a citizen of the United States, residing in the Borough of Manhattan, county, city, and State of New York, have invented a new, original, and ornamental Design for a Hat or the like, of which the following is a specification, reference being had to the accompanying drawings, forming part thereof.

On the drawings:

Fig. 1 is a front elevational view of a hat showing my new design;

Fig. 2 is a side elevational view of the hat shown in Fig. 1; and

Fig. 3 is a plan view of the hat shown in Fig. 1.

The essential features of the design reside in the portions shown in solid lines.

I claim:

The ornamental design for a hat or the like, substantially as shown and described.

JACK ENDELSO.
